METHOD OF FILLING CAPSULES

Daniel Darley Smith, Valdosta, Ga.

Application January 18, 1940, Serial No. 314,514

4 Claims. (Cl. 226—41)

This invention relates to methods for filling of containers, such as capsules, or the like with powdered or finely ground material.

This invention is an improvement over the structure embodied in my Patent No. 2,155,336 which issued April 17, 1939.

An object of this invention is to provide a method which may be used by a druggist, hospital or the like whereby a number of capsules or like containers may be filled at one time in such a manner that a predetermined quantity of material will be placed in each capsule.

Another object of this invention is to provide a method for use in filling containers, receptacles or the like wherein powdered material, such as quinine which has a tendency to cake or form into granules, may be placed in the containers or capsules in an accurate quantity.

A still further object of this invention is to provide a method which will pack the material in the capsules or containers simultaneously with the closing or sealing thereof.

To the foregoing objects and to others which may hereinafter appear, the invention consists of a novel method which is hereinafter referred to and illustrated in the accompanying drawings, wherein is shown an embodiment of the invention, but it is to be understood that changes, variations and modifications may be resorted to which fall within the scope of the invention as claimed.

In the drawings:

Figure 1 is a vertical section through the combined capsule positioning and holding means forming the first step in the filling of the capsule,

Figure 2 is a view similar to Figure 1 with an added element for guiding the material and the other capsule part,

Figure 3 is a vertical section partly in detail showing the manner of levelling the material and maintaining the material above the open capsule parts,

Figure 4 is a fragmentary vertical section of the apparatus showing a material compacting device,

Figure 4a is a fragmentary sectional view taken on the line 4a—4a of Figure 3,

Figure 5 is a fragmentary vertical section through the device with the material separator positioned therein,

Figure 6 is a detail front elevation partly in vertical section of the capsule filling means in the agitator,

Figure 7 is a detail front elevation partly brok-

en away and in section of the capsule actuating or telescoping means,

Figure 8 is a fragmentary vertical section showing one capsule with the parts thereof in their respective positions prior to the operation of the capsule actuating or telescoping plungers.

Figure 9 is a view similar to Figure 8 showing the capsules in telescoping position with the material packed therein,

10 Figure 10 is a vertical section partly in detail showing the step in the method following the uniting of the capsules,

Figure 11 shows a subsequent step wherein the capsules are ejected from the holder,

15 Figure 12 is a detail side elevation of the capsule filling means,

Figure 13 is a top plan view partly broken away of the combined capsule holding and positioning means,

20 Figure 14 is a top plan of the material divider, Figure 15 is a detail top plan of the assembled capsule filling means,

Figure 16 is a fragmentary top plan of the capsule and material guiding means, and

25 Figure 17 is a fragmentary sectional view taken on the line 17—17 of Figure 7.

Referring to the drawings, the first to Figure 1, the capsules which are to be filled are initially divided or separated and the part of the largest diameter which is known as the cap and which is designated 20 is mounted in a socket formed in a combined capsule holding and positioning means including a plate 21 which is provided with a plurality of sockets 22 therein. A second plate 23 which engages on the upper surface of the plate 21 is provided with a plurality of openings 24 which register with the sockets 22. The lower plate 21 is provided with a plurality of upwardly extending dowels or pins 25 which engage in openings 26 provided in the plate 23 so that the openings 24 will be disposed in register with the sockets 22. The capsule parts 20 are adapted to snugly engage in the openings 24 and the sockets 22 and the upper ends of the capsule parts 20 are adapted to be substantially flush with the upper surface of the upper plate 23.

After all of the sockets 22 and the openings 24 have been filled with the empty capsule parts 20, a block or body 27 is positioned on top of the upper plate 23. The upper plate 23 is provided with a plurality of upwardly projecting dowels 28 which engage in openings 29 formed in the body or block 27. The body or block 27 is provided with a plurality of vertically disposed openings 30 which register with the openings 24 and pref-

erably are of a diameter less than the diameter of the openings 24. The openings 30 at their upper ends are flared as at 31 forming a material guiding means to guide the material downwardly through the openings 30 as will be hereinafter described.

The lower plate 21 is provided with pivoted hooks or holding members 32 and the body 27 is provided with outwardly extending pins 33 for engagement with the hooks 32. The upper plate 23 is also provided with a pair of hooks 34 which are pivotally secured thereto and the hooks 34 are adapted to engage outwardly projecting pins 35 carried by the block or body 27. In this manner the lower plate 21 can be released from the block 27 without releasing the upper plate 34.

A substantially rectangular hopper 36 is adapted to engage the upper surface of the body or block 27 and is provided with a plurality of dowels or positioning members 37 which are engageable in the openings 29 so as to properly position the hopper 36 relative to the body 27. The hopper 36 is open at its upper and lower ends and the lower end of the hopper 36 is adapted to be initially closed by means of a slide or removable bottom wall 38 which is provided at one end with a handle 39. The slide or bottom wall 38 is initially interposed as shown in Figures 3, 4 and 4a between the hopper 36 and the upper surface of the apertured body or block 27 so that when the material is initially placed in the hopper 36 the material will not fall downwardly into the openings 30. A measured quantity of powdered material M is placed in the hopper 36 on top of the slide or bottom wall 38 and then a levelling blade 39' carried by a pair of handles or bars 40 is adapted to engage the material M. The two bars 40 are clamped together by means of bolts or clamping members 41 so that the blade 39' may be vertically adjusted relative to the slide 38. The lower edges of the bars or blade supporting members 40 are adapted to slidably engage the upper edges of the hopper 36 so that the blade 39' may be moved back and forth in order to properly level the powdered material within the hopper 36.

After the material M has been properly levelled off, this material is adapted to be compacted by means of a compacting device including a plate 42 having a handle or bale 43 secured thereto. This plate 42 is of a size such that it will readily engage within the hopper 36 and the plate 42 is adapted to be manually forced downwardly within the hopper 36 to compact the material as shown in Figure 4.

When the material M has been levelled and compacted, this material is then divided or separated by means of a divider or separator shown in top plan in Figure 14. This divider or separator generally designated as 44 comprises a rectangular frame 45 and a plurality of intersecting partitions 46 forming material receiving compartments 47 which are adapted to register with the openings 30. A handle 48 is secured to the frame 45 and provides a means whereby the divider or separator 44 may be readily positioned within or removed from the hopper 36.

After the material has been separated as shown in Figure 5, the slide or bottom wall 38 is pulled out from beneath the hopper 36. The material M may then gravitatingly drop downwardly in the openings 30 being guided by the flared upper end portions 31. Where the material is of a character such that the particles

thereof will not form into granules, the separated material in the compartments or chambers 47 will freely drop downwardly through the openings 30 into the capsule part 20 with a portion of the material extending upwardly above the capsule part 20. However, where material such as quinine is being placed in the capsules, the material will not readily drop downwardly by gravity into the openings 31. In order, therefore, to provide a means whereby the separated material may be discharged or forced downwardly from the chambers 47 into the openings 30 and the capsule parts 20, I have provided an agitator or shaker generally designated as 49. The agitator or shaker 49 comprises a base 50 and upwardly extending supporting bars 51. The bars 51 are secured as at 52 to the base 50 and a transversely disposed supporting means 53 is secured between the upper ends of the vertical bars 51.

A platform 54 is disposed between the uprights 51 and is yieldably supported above the base 50 by means of springs 55. The springs 55 are secured by fastening means 56 to the underside of the platform 54 and the lower ends of the springs 55 engage dowels or pins 57 which are secured to the base 50. A pair of L-shaped stop bars 58 are secured to the uprights 51 above the base 50 and are adapted to limit the downward movement of the platform 54. Normally, the platform 54 is disposed slightly above the angle bars 58. The capsule loading or filling means hereinbefore described is positioned on the platform 54 between upwardly projecting flanges 59 carried by the marginal portions of the platform 54. The locked loading or filling means includes the two lower plates 21 and 23 which are releasably locked by the hooks 32 and 34 to the block 27. The hopper 36 having the divider or separator 44 positioned therein is also disposed on top of the block or body 27. A transversely disposed bar 60 provided at the opposite ends thereof with downwardly projecting blocks 61 is positioned on top of the hopper 36. The blocks 61 are provided with offset portions 62 engaging on the outer sides of the hopper 36 so as to hold the bar 60 against endwise movement relative to the hopper 36.

A flat spring 63 is secured by fastening devices 64 to the under side of the bar 60 and this spring 63 is adapted to engage the upper central portion of the divider or separating member 44 so as to hold this divider or separating member against outward movement during the agitation or shaking of the capsule loading means. A rubber bumper 65 is secured by fastening means 66 to the upper surface of the bar 60 in substantially the center thereof and a spring-pressed plunger 67 which is slidable in a guide 68 carried by the supporting means 53 is adapted to engage the bumper 65. The plunger 67 includes a head 69 and a stem 70 which extends upwardly through the guide means 68. A head 71 is secured to the stem 70 above the guide means 68. A spring 72 is disposed within the guide means 68 at its lower end engages against the head 69 and at its upper end engages against an inwardly projecting flange 73 formed with the guide 68. A plunger operating member comprising a plate 74 having a plurality of teeth 75 is rotatably mounted between a pair of upwardly projecting bearings 76. The plate 74 is fixed to a shaft 77 and a handle 78 is also fixed to the shaft 77. The teeth 75 are adapted to engage beneath the head 71 so that the plunger 67 will be raised against

the tension of the spring 72 when the crank 73 is rotated. In this manner the raising of the plunger 67 will permit the springs 55 to raise the platform 54 off of the angle members 58 and when the head 71 is released from a tooth 75, the spring 72 will force the plunger 67 downwardly.

The capsule loading means is yieldably held on the platform 54 by means of a pair of springs 79 which at the lower ends engage outwardly projecting headed pins 80 carried by the platform 54 and at their upper ends engage outwardly projecting headed pins 81 which are carried by the opposite ends of the bar 60. The springs 79 are adapted to be releasably engaged with the pins 81 so that when the capsule loading device is positioned on the platform 54 the springs 79 may be engaged with the pins 81. This may be accomplished by providing relatively large eyes at the upper end of the springs 79 which engage over the heads of the pins 81.

After the material in the chambers 47 has been discharged into the capsule part 20 and in the openings 30 of the body or block 27 the capsule loading means may be removed from the agitator 49. The hopper 36 with the divided 44 may also be removed from the body 27. At this time a second capsule part or body 82 is inserted in the openings 30 and permitted to move freely downwardly in the openings 30. In order to provide a means whereby the capsule parts 82 may be united in telescopic relation with the capsule parts 20 and at the same time the material M may be compacted within these parts, I have provided a compressing structure formed of a plurality of plungers 83 secured at one end to a head or block 84. These plungers 83 are provided at their lower or free ends with a concave seat 85 within which the rounded upper end of the capsule part 83 is adapted to engage. The capsule parts 82 are substantially smaller in diameter than the capsule parts 20 and are adapted to telescopically engage within the capsule parts 20. Where only a small number of capsules are being filled, the plunger body 84 may be manually forced downwardly relative to the block 27 and in order to provide a means whereby the plungers may be limited in their downward movement, I have provided a pair of stop members 86 on each side of the block 84. These stop members 86 comprise a bar or plate 87 provided with notches 88. The upper end of the plates or bars 87 are pivotally secured on pivots 89 carried by the body 84. The body 27 on each side thereof is provided with a pair of stop pins 90 which are adapted to engage in selected notches 88 so as to thereby limit the downward movement of the plungers 83. Each pair of stop members 86 are connected together by means of a link 91 which is pivotally secured as at 92 to each pair of limiting members 86.

However, where all of the openings 24 and sockets 22 are filled the plungers 83 cannot readily be moved downwardly by manual pressure on the block 84. In this case, the capsule loading means including the body 27 and the two plates 21 and 23 are mounted between a pair of pressure plates 93 and 94. The plungers 83 and the block 84 are at this time in operative position relative to the block 27 and the limiting members 86 have moved to a released position relative to the stop pins 90.

The plate 94 comprises a movable platform or plate and is mounted on a plunger 95 forming part of a jack structure 96. The jack structure 96 is constructed in the form of a hydraulic

jack provided with a pump 97 and an operator 98. The jack 96 is mounted on a base plate 99 and a plurality of upright bars 100 are secured at the lower ends to the plate 99. These bars 100 are provided with threaded upper portions 101 and nuts 102 and 103 engage on opposite sides of the upper or stationary plate 94 so as to fixedly secure the plate 94 on the uprights 100. A pair of nuts 104 and 105 are also threaded on the bars 100 below the plate 94 and provided a means whereby the movable pressure plate 93 may be limited in its upward movement.

When the operator 98 is actuated the plunger 95 will be raised and the pressure plate 93 will also be raised carrying therewith the capsule loading means including the plates 21 and 23, the block 27 and the plunger carrying block 84. The block 84 will engage the stationary plate 94 upon upward movement of the pressure plate 93 so that the plungers 83 will be moved downwardly through the openings 30 and force the inverted capsule part 82 into telescopic relation relative to the capsule part 20. The pressure plate 93 will move upwardly to the limit permitted by the stop nuts 105 which are locked by the lock nuts 104. Pressure on the plunger 95 may be released by means of a releasing valve 106 forming part of the jack structure 96 and when the pressure has been released the plunger 95 and the pressure plate 93 are moved downwardly by means of a pair of compression springs 107 which are secured as at 108 to the base 99 and by means of hooks 109 to the pressure 93.

The capsules at this time are in a completely filled and packed condition and the capsule loading device is then removed from the pressure structure shown in Figure 7 and the entire structure is inverted as shown in Figure 10. The bottom plate 21 is then released thereby exposing a portion of the socket parts 20 which protrude through the plate 23. When the plungers 83 have moved inwardly of the block 27 to the limit permitted by the stop nuts 105 or the stop members 86, the block 84 will be positioned in spaced relation to the adjacent face of the body or block 27. After removing the bottom plate 21 the stop members 86, where attached, may be released so that the body 27 and the plate 23 may be pushed downwardly until the body 27 contacts with the body 84. This is the position of these two parts shown in Figure 11. Downward movement of the body 27 will cause the telescoped capsule parts 20 and 82 to be moved upwardly for a distance sufficient to eject the capsule part 20 from the openings 24. The capsule part 82 is substantially smaller in diameter than the diameter of the openings 24 so that when the telescoped parts are in the position shown in Figure 11, these capsule parts may be readily removed from the loading device by again inverting the device or shaking out the loaded capsules.

With a device of this kind, a number of capsules may be accurately loaded at one time with the desired material, the maximum number of capsules being limited by the number of sockets and openings provided in the two plates 21 and 23 and apertured body 27. However, where it is desired to use this device for filling a smaller number of capsules, a reduced size hopper may be used wherein the dowels 37 will engage within selected openings 30 of the body 27. A reduced size slide or bottom wall 38 will be used with the reduced hopper. In other respects, the entire apparatus may be used or if the number of capsules is small enough, the pressure device shown

in Figure 7 may be eliminated and the plungers 83 may be forced downwardly by manual pressure on the block 84.

Where the block 84 is manually forced downwardly, the stop members 86 will be used and will be swung to the position shown in Figure 12. In order to provide an auxiliary stop means for the pressure plate 93, I have provided a substantially U-shaped slide member 110 which is slidable on the opposite edge portions of the pressure plate 93. This auxiliary stop member 110 is provided with slots 111 through which the uprights 100 loosely project and pairs of blocks 112 are secured to the opposite parallel legs of the slide member 110 and are adapted upon inward movement of this slide member to be disposed for engagement with the stop nuts 104. The parallel legs of the slide member 110 are slidably secured to the pressure plate 93 by means of a pair of fastening devices 113 engaging through slots 114 provided in the parallel legs of the slide member 110. The bight 115 of the slide member 110 comprises a handle by means of which the slide member may be pulled outwardly to a released position where desired.

With the use of a method as hereinbefore described, a predetermined quantity of material may be initially placed in the hopper 36 and this material then levelled off and compacted by the compacting means 42 and 43. The separator 44 is then forced downwardly through the compacted material until the separator 44 engages the slide or bottom wall 38. The separator 44 provides a means whereby the levelled and compacted material will be separated into predetermined quantities so that only the quantities of separated material in each compartment will be discharged into the capsule parts 20 and the openings 30 of the block 27. In this manner an accurate quantity of material will be placed in the openings 30 and the capsule parts 20 and this material will then be completely packed within the telescoped capsule parts.

What I claim is:

1. The method of simultaneously filling a plurality of capsules which includes positioning the

capsule caps beneath a predetermined quantity of material, supporting the caps throughout their length, levelling the material above the caps, dividing the material into as many divisions as there are caps, agitating the divided material whereby the material will gravitate into said caps, telescoping a capsule body into each cap and simultaneously packing the material in the capsule while said cap is so supported.

5 2. The method of simultaneously filling a plurality of capsules which includes positioning a plurality of capsule caps beneath a predetermined quantity of material, supporting the caps throughout their length, levelling the material 15 above the caps, packing the material above the caps, dividing the material into as many divisions as there are caps, agitating the divided material whereby the material will gravitate into said caps, telescoping a capsule body into each cap and simultaneously packing the material in the capsule while said cap is so supported.

20 3. The method of simultaneously filling a plurality of capsules which includes positioning a plurality of capsule caps beneath a predetermined quantity of material, supporting the caps throughout their length, levelling the material above the caps, dividing the material into as many divisions as there are caps, gravitationally discharging the material into said caps, telescoping a capsule body into each cap and simultaneously packing the material in the capsule while said cap is so supported.

25 4. The method of simultaneously filling a plurality of capsules which includes positioning a plurality of capsule caps beneath a predetermined quantity of material, supporting the caps throughout their length, levelling the material above the caps, packing the material above the caps, dividing the material into as many divisions as there are caps, gravitationally discharging the material into said caps, telescoping a capsule body into each cap and simultaneously packing the material in the capsule while said cap is so supported.

30

DANIEL DARLEY SMITH.
